UNITED STATES PATENT OFFICE

ROBERT C. RUSSELL AND JOSEPH CLIFFORD RUSSELL, OF PITTSBURGH,
PENNSYLVANIA

FILING DEVICE

Application filed December 23, 1929. Serial No. 416,082.

This invention relates to filing devices and the primary object is to provide an index of this character, which will be more compact than those heretofore known, so that a larger number of cards may be stored in a given amount of space, and a greater number of cards may be arranged on each drawer or board of the structure.

A further object is to furnish an index of this type, comprising novel card-supporting bars which are shaped to facilitate the passage of a card thereinto, and which are so designed as to allow the card to lie substantially parallel to the supporting board or drawer.

Our present construction allows much narrower card-supporting bars to be used than if each bar had a plain slot cut therein.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawings,

Fig. 1 is an elevation of a visible index drawer or board constructed in accordance with our invention, and shown supporting a number of cards and their support bars.

Fig. 2 is an enlarged sectional view of the same, on the line 2—2 of Fig. 1.

Fig. 3 is an enlarged sectional view on the line 3—3 of Fig. 1.

Fig. 4 is a perspective view of one of our improved card-supporting bars.

Fig. 5 is a perspective view of one of the sliding lock plates that are employed to keep the supporting bars in position.

Fig. 6 is an enlarged perspective view of a portion of one of the card-supporting bars, and illustrating the inclined lips which form a guideway into which a card is inserted.

Fig. 7 is a perspective view of a corner portion of one of the cards.

In the drawings, 8 indicates a drawer or board formed of sheet-metal, one side edge portion of which is bent inwardly to provide a guideway or groove 9. The lower edge portion 10 of the drawer is bent forwardly at right-angles to the back of the drawer to re-

inforce the latter. The top edge 11 is bent forwardly in the same way, and it will be noted that the edge portions 10 and 11 close the ends of the groove 9.

The other side edge portion of the drawer is provided with a channel-shaped guiding member 12, that is preferably formed of sheet-metal and secured to the back of the drawer by any suitable means, such as riveting or the like. The guide 12 is equipped with flanges 13 which extend toward one another, and slidably interlock with outwardly extending flanges 14 on sheet-metal locking plates 15.

It will be noted that the guide 12 extends the full length of the drawer, and that there are a number of locking plates 15 slidably cooperating therewith. The lower one of these locking plates is rigidly connected to an extension member 16 that is hinged at 17 to a master locking plate 18 which can swing on the hinge, but which is normally maintained in alignment with the plates 15 by means of a suitable spring-latch 19. When the plate 18 is swung forwardly, after being released by the latch, it is obvious that all of the plates 15 may slide downwardly to some extent on the guide 12. This arrangement allows the locking plates to be shifted for the purpose of releasing the card-supporting bars which will be described hereinafter. At this point, it will be noted that the plates 15 extend inwardly beyond the inner edge of the guide 12, so as to provide a groove 20 which is arranged opposite the groove 9, and also extends practically the full length of the drawer.

A supplemental metal sheet 21 is secured to the face of the part 8, and its side edges extend into the grooves 9 and 20. This sheet is secured to the part 8 by any suitable means, and forms with the part 8, a pocket 22 to receive the lower ones of the cards 23, when the latter are inserted in the index. From Fig. 7 it may be seen that each card has at its upper corners, projecting shoulders 24, and when the cards are inserted in the supporting bars 25, these shoulders rest on ears 26 which are struck forward from each of the supporting bars.

As before stated, these supporting bars are of special construction, and are designed to permit a greater number of cards to be mounted on a tray than was heretofore possible. Each bar is preferably of sheet-metal, and is relatively narrow from end to end, and its extremities are curled, as shown at 27, to provide enlargements which engage and can slide in the grooves 9 and 20. As 10 the terminals 27 are curled rearwardly, it may be seen from Fig. 3 that they act to space the body of the bar from the backing 8, so as to allow a number of thin cards 23 to lie between the bar and the backing 8, as 15 may be seen from Fig. 2.

Heretofore, we have proposed slotted card-supporting bars, but such bars had plain slots. In our present invention, the slot 28 of the bar is defined by upper and lower inclined lips 29 and 30, so that a card may be inserted through the slot while the card is substantially parallel to the bar. In other words, the lips defining the slot provide an inclined mouth which is arranged at an obtuse angle to the straight portions 31 and 32 of the bar. Consequently, when a card is inserted into the slot, it will lie substantially at an acute angle to the bar.

The upper lip 29 extends rearwardly and 30 downwardly, while the lower lip extends forwardly and upwardly. We prefer to form the ears 26 from parts of the upper lip 29, but the ears are extended forwardly instead of rearwardly.

35 For the purpose of securing each card to its supporting bar, the latter is provided intermediate its ends, with a forwardly projecting tongue 33 which is also formed from a part of the lip 29, and is extended forwardly so as to pass through a slit formed in the upper portion of the card.

When a card is to be inserted or removed, the plate 18 may be unlatched and swung forwardly, and then the locking plates 15 45 can be shifted so as to release the supporting bars 25. Now the supporting bar and its card may be extracted from the drawer, and after the assembly has been extracted, the card may be changed by drawing the same upwardly from the slot after the slit in the card has been released from the retaining tongue 33.

From the above description, taken in connection with the accompanying drawings, it 55 will be appreciated that we have devised a visible card index which will allow a greater number of cards to be arranged on a drawer than was heretofore possible, and which will permit the entire index to be made much 60 smaller and more compact than those heretofore known.

While we have disclosed what we now consider a preferred embodiment of the invention, we are aware that various changes may 65 be made in the details disclosed, without de-

parting from the spirit of the invention, as expressed in the claims.

What we claim and desire to secure by Letters Patent is:

1. A visible index including a card-supporting bar provided intermediate its upper and lower edges with a slot into which a card may be inserted, said bar having inclined portions functioning to hold a card at an acute angle relatively to the bar. 70

2. A visible index including a slotted card-supporting bar having inclined lips between its upper and lower edges functioning to hold the card substantially at an acute angle to the bar. 75

3. A visible index including a slotted card-supporting bar having a downwardly and rearwardly inclined lip arranged at the top of the slot. 80

4. A visible index including a slotted card-supporting bar having a forwardly and upwardly inclined lip arranged at the bottom of the slot. 85

5. A visible index including a slotted card-supporting bar having along its slot, a rearwardly and downwardly inclined lip and a forwardly and upwardly inclined lip, the first mentioned lip being arranged above the slot, and the other lip being arranged below the slot. 90

6. A visible card index comprising a slotted card-supporting bar provided with a slot between its upper and lower edges and having its end portions bent to form enlargements adapted to space the body of the bar from a supporting surface, and a card supported by said bar and extending through said slot. 100

7. A visible index comprising a card-supporting bar having inclined lips defining an inclined guideway between the upper and lower edges of the bar, portions of the bar being bent forwardly to provide card-supporting ears. 105

8. A visible index comprising a slotted card-supporting bar having inclined lips defining an inclined guideway between the upper and lower edges of the bar, a portion of the bar extending forwardly and forming a card-retaining tongue. 110

9. A visible index comprising a drawer having oppositely disposed grooves, a series of card-supporting bars having their ends extending into said grooves, each bar being provided with inclined surfaces defining an inclined guideway between the upper and lower edges of the bar, cards extending through said guideways, and means on the bars for supporting said cards. 115

10. A visible index comprising a drawer having oppositely disposed grooves, a series of card-supporting bars having their ends extending into said grooves, each bar being provided with inclined surfaces defining an inclined guideway, and cards extending 120

through said guideways, each card having projecting shoulders, and each bar having supporting ears adapted to engage said shoulders.

5 11. A visible index comprising a drawer having oppositely disposed grooves, a series of card-supporting bars having their ends extending into said grooves, each bar being provided with inclined surfaces defining an inclined guideway, cards extending through

10 said guideways, the ends of each bar being bent to form enlargements which engage the grooves and function to space the body of the bar from the face of the drawer, and

15 means on the bars for supporting said cards.

12. A visible index comprising a drawer having oppositely disposed grooves, a series of card-supporting bars having their ends extending into said grooves, each bar being

20 provided with inclined surfaces defining an inclined guideway, and cards extending through said guideways, each card having a slit, and each bar having a retaining tongue adapted to fit in the slit of the card to sup-

25 port a card in said guideway.

13. A relatively narrow card-supporting bar formed of sheet-metal and having its end portions curled rearwardly to provide reinforcing enlargements, the bar having upper
30 and lower inclined lips defining an inclined guideway, one of said lips having portions thereof extending forwardly and forming card supports.

14. A relatively narrow card-supporting
35 bar formed of a single thickness of sheet-metal and having its end portions curled rearwardly to provide reinforcing enlargements, the bar having upper and lower inclined lips defining an inclined guideway, portions of
40 said bar extending forwardly and forming card supports.

In testimony whereof, we have signed this specification.

ROBERT C. RUSSELL.
